CLAIM

The ornamental design for an display screen or portion thereof with animated life event simulator graphical user interface as shown and described.

DESCRIPTION

FIGS. 1-3 are front views of example Event Icons used within the display screen or portion thereof with animated life event simulator graphical user interface according to the claimed design, shown enlarged for completeness of illustration;

FIG. 4 is a front view of a first image in a sequence of a display screen or portion thereof with animated life event simulator graphical user interface including the Event Icons according to the claimed design;

FIG. 5 is a front view of a second image in the sequence; FIG. 6 is a front view of a third image in the sequence; FIG. 7 is a front view of a fourth image in the sequence; FIG. 8 is a front view of a fifth image in the sequence; FIG. 9 is a front view of a sixth image in the sequence; FIG. 10 is a front view of a seventh image in the sequence; FIG. 11 is a front view of an eighth image in the sequence; FIG. 12 is a front view of a ninth image in the sequence; FIG. 13 is a front view of a tenth image in the sequence; FIG. 14 is a front view of an eleventh image in the sequence; FIG. 15 is a front view of a twelfth image in the sequence; FIG. 16 is a front view of a thirteenth image in the sequence; FIG. 17 is a front view of a fourteenth image in the sequence; FIG. 18 is a front view of a fifteenth image in the sequence; and,

FIG. 19 is a front view of a sixteenth image in the sequence including Event Indicator and Description Icons.

The broken line at the periphery of the graphical UI in FIGS. 4-19 illustrate a portion of the display screen. The remaining

(Continued)

broken lines in FIGS. 4-19, including all text in each of the Figures shown in broken font, illustrate portions of the animated graphical user interface. None of the broken lines in the Figures form part of the claimed design. The subject matter depicted herein includes a process or period in which an image changes into another image. This process or period forms no part of the claimed design.
